Attest.

United States Patent Office.

EZRA HUTSON, OF BROCKPORT, NEW YORK.

Letters Patent No. 70,853; dated November 12, 1867.

IMPROVEMENT IN REELS AND SWIFTS.

The Schedule referred to in these Letters Patent and making part of the same.

TO ALL WHOM IT MAY CONCERN:

Be it known that I, EZRA HUTSON, of Brockport, in the State of New York, have invented certain new and useful Improvements in Reels; and I do hereby declare that the following is a full, clear, and exact description of the same, reference being had to the accompanying drawings, and to the letters of reference marked thereon, in which—

Figure 1 is a side elevation.

Figure 2 a longitudinal transverse section of the arm and sleeve, with the metal plates which hold the reel or swift-arms removed, and

Figure 3 a plan view, showing the relative position of the reel-arms.

The nature of my invention consists in the employment and combination of the several devices hereinafter described, for the purpose already stated.

A represents a metal stock, provided with projection *b* and thumb-screw *a*, in order that it may be secured to a table or bench. *d* is a cog-wheel, pivoted to stock A, as fully shown in fig. 1, the object of which will be shown hereafter. Upon this cog-wheel is the pin *e*, which operates spring *f*, for the purpose of indicating the exact number of revolutions of the reel, or the precise number of threads in the hank. B represents an arm, a ring being formed at one end, as seen in fig. 2. This ring slips over a round projection on stock A, and is retained in its place by the metal washer *g* and thumb-screw *h*. C represents a sleeve, fitting loosely over the arm B. Said sleeve is provided with a perpetual screw, by means of which the cog-wheel *d* is operated. *k k'* are two metal plates, each being provided with two grooves for the reception of the reel-arms D D. It should be observed that the plate *k'* is screwed tightly upon the sleeve C, while *k* fits loosely upon it, thus admitting of the arms D D being placed at right angles, parallel, or in any relative position desired. When suitably adjusted, the thumb-screw *m* holds them securely. *i* is a screw, which enters the end of arm B for the purpose of preventing the sleeve C from slipping off. The arms D D are furnished at their ends with wire-holders E E. *p p* are projections, for the purpose of acting as checks to arm B.

The operation of my machine is as follows: The arms D D being properly adjusted, both as regards their relative positions and the size of the hank, motion is given to them. If it be desirable to know the number of threads wound off, allow the sleeve C to rest upon the cog-wheel *d*. Motion being thus conveyed to said wheel, by means of the perpetual screw, the pin *e* will cause the spring *f* to make a noise upon every revolution of the wheel, thus indicating precisely the number of threads in a hank. It will be observed that the arm B can be secured at any angle desired.

Having thus fully described my invention, what I claim, and desire to secure by Letters Patent, is—

1. The sleeve C, in combination with the pivoted arm B, substantially as and for the purpose specified.
2. The combination of plates *k k'*, arms D D, sleeve C, and arm B, as and for the purpose set forth.
3. Spring *f*, wheel *d*, sleeve *e*, and arm B, all combined substantially in the manner and for the purpose described.

In testimony that I claim the above, I affix my signature in presence of two witnesses.

EZRA HUTSON.
